CLAIM

The ornamental design for a multi-function blood measuring apparatus as shown and described.

DESCRIPTION

1. Multi-function blood measuring apparatus

1.1 : Perspective

1.2 : Front

1.3 : Back

1.4 : Left

1.5 : Right

1.7 : Bottom

1.8 : Perspective

This is an application for a certain new, original and ornamental design for a multi-function blood measuring apparatus. The disclosure relates to a multi-function blood measuring apparatus that is capable of measuring blood glucose, and blood pressure in a single apparatus. The broken lines in the drawing depict portions of the multi-function blood measuring apparatus that form no part of the claimed design.

1 Claim, 8 Drawing Sheets
